(57) **CLAIM**

The ornamental design for a two-handed scraper, as shown and described.

DESCRIPTION

FIG. 1 is a top plan view of the two-handed scraper showing my new design; the fixing and support elements are shown in dotted lines for illustrative purposes only and form no part of the claimed design;

FIG. 2 is a right side view thereof, the left side view being a mirror image thereof;

FIG. 3 is a bottom plan view thereof; and,

FIG. 4 is a front end view thereof.
